UNITED STATES PATENT OFFICE.

THOMAS H. SEELEY, OF MALDEN, MASSACHUSETTS, ASSIGNOR TO UNITED SHOE MACHINERY CORPORATION, OF PATERSON, NEW JERSEY, A CORPORATION OF NEW JERSEY.

LASTING MACHINE.

Application filed September 3, 1918, Serial No. 252,405. Renewed January 29, 1923.

To all whom it may concern:

Be it known that I, THOMAS H. SEELEY, a citizen of the United States, residing at Malden, in the county of Middlesex and 5 State of Massachusetts, have invented certain Improvements in Lasting Machines, of which the following description, in connection with the accompanying drawings, is a specification, like reference characters on the 10 drawings indicating like parts in the several figures.

The present invention is herein shown and described with particular reference to its application to machines for lasting boots 15 and shoes although in various of its aspects the invention is not restricted to such use. In the drawings the invention is illustrated as embodied in a lasting machine, which works on different portions of the upper 20 materials successively, of the type known as hand method machines. A machine of this type is disclosed in Letters Patent of the United States No. 584,744, granted June 15, 1897, upon an application of Ladd 25 and McFeely.

Although a machine embodying this invention is herein described with special reference to its use in lasting the sides and shoes including a portion of the heel seat 30 near the breast line, it is to be understood that the invention is equally applicable to machines of this type when organized for use in lasting other portions of a shoe. In machines of the hand method type, a gripper 35 is actuated to grip and pull or updraw the upper materials and to overdraw or lay them upon the innersole and a wiper is given movement to engage the upper materials and press or wipe them into lasted 40 position upon the innersole. The upper materials are secured in such position by tacks which are fed into an aperture in the wiper prior to each advance movement thereof and are driven by tack driving 45 means at the conclusion of the wiper advance. Machines of this type are also provided with means for imparting a lateral and turning movement to the gripper to plait the upper materials at those portions 50 of the shoe where excessive fullness of the stock occurs. Means under the control of a knee lever is provided which enables the operator to cause the gripper to plait the upper materials to the desired degree where plaiting is necessary or desirable and to 55 suspend the plaiting movements at other portions of the shoe.

A usual practice in lasting shoes, for example, welt shoes, is to last the sides and the portion of the shoe at the breast end of 60 the heel seat upon a hand method machine and to last the toe and complete the lasting of the heel seat on a bed lasting machine. In lasting the sides of a shoe, the upper is updrawn and overdrawn by the gripper, 65 wiped in by the wiper, and secured by long tacks which are left upstanding for convenience in subsequent removal. The upper plaiting mechanism is used when desired, particularly in conforming the upper to the 70 last in the deeply undercut shank portion on the inner side of the shoe. To position the shoe for this operation, the machine is provided with an edge gage having but slight vertical extent and adapted to reach 75 in over the shank of the shoe, this gage being generally referred to as a thin edge gage. When the portion of the side adjacent to the breast end of the heel seat is reached, it is necessary to provide an edge 80 gage of considerable vertical extent which is adapted to conform the upper and heel stiffener closely to the last at this portion of the shoe. This gage is known as a thick edge gage. To secure the upper at this portion of the shoe, it is desirable to drive completely a few tacks of a different kind which tacks are clinched on the heel plate 85 of the last and remain permanently in the shoe to hold the upper and wings of the 90 heel stiffener in proper position at the two sides of the shoe adjacent to the breast end of the heel seat. Frequently two or three tacks are driven at this time in each side of this portion of the shoe. When the machine 95 is set for lasting the side of the shoe and it is desired to change the machine for lasting the heel seat, it will be noted that the following changes are necessary: First, the thick edge gage must be presented in a 100 position different from that of the thin edge gage in order to position the work properly.

for this operation; second, the kind of tacks supplied to the wiper must be changed from tacks adapted for partial insertion to hold the upper at the side of the shoe to tacks adapted to be completely driven and remain permanently in the heel seat of the shoe; and third, the stroke of the driver must be changed from a partial stroke to a complete stroke which drives the tacks fully in and clinches them. In United States Letters Patent No. 1,254,917, granted January 29, 1918, upon application of Ronald F. McFeely, mechanism is shown which, by the operation of a lever located on the right hand side of the machine, may be shifted to effect the changes above mentioned. In the use of this machine, when it is required to shift the mechanism, the operator is obliged to let go of the shoe, operate the lever, then grasp the shoe again and reposition it for the new operation. A general object of this invention is to enable the operator to shift the mechanism without releasing the shoe with either hand and to minimize the time and labor required to effect the shift.

In lasting the sides of the shoes, it is recognized by shoe makers as desirable and it is the usual practice in hand lasting, to last each side of the shoe from the toe toward the heel and then to drive a tack or tacks on each side of the heel seat near the breast line. Should the hand laster drive the heel seat tacks first and then last the side, he would frequently find that, after lasting the side, it would be necessary to remove the heel seat tacks and to relast that portion of the shoe. In the use of the hand method machine for this work, as previously constructed, operators, in order to gain time, have adopted the practice of first lasting the sides of the shoe, then shifting the mechanism and inserting the heel seat tacks, then taking the second shoe and, without shifting the mechanism back to its original position, inserting the heel seat tacks first, and then shifting the mechanism for side lasting and lasting the sides. This, of course, leaves the machine ready for lasting first the sides of the third shoe, the same as on the first shoe. Thus, every other shoe is lasted in the proper manner and every other shoe is lasted in a manner which is recognized as less desirable but which is sufficiently good to pass inspection in the general run of work. The operator, by this practice, cuts the time required for shifting in half and this is sufficient inducement to cause him to take the risk of having to do some shoes over.

A further object of this invention is to provide a machine by which the time required for effecting the shifting of the machine from the condition for operation on one kind of work to the condition for operation on another kind of work is so reduced as to render it practicable to last each side of

the shoe in the proper manner and still enable the operator to last more shoes than is possible on machines of the prior construction even when half the shoes are improperly lasted, as above explained.

Features of the invention consist in a novel machine organization adapted to perform one operation upon a shoe when in one condition and adapted to be shifted to another condition to perform another operation upon a shoe, and means under control of the operator for effecting by power the shifting of the mechanism from the condition for performing one operation to the condition for performing the other operation. The invention is herein disclosed as embodied in a lasting machine organized to last one portion of a shoe and then, upon a shift being made in the mechanism, to last another portion of the shoe, combined with means under the control of the operator for effecting the shifting of the mechanism from position for lasting one part of the shoe to position for lasting another part of the shoe by power operation of the machine.

A further feature of the invention consists in lasting means including a wiper moved to and fro across the last bottom for progressively lasting a shoe, means to secure the upper at a side of the shoe constructed and arranged for adjustment differently to secure the upper at an end of the shoe, shoe positioning means to locate the shoe for side lasting constructed and arranged for adjustment differently to locate the shoe for end lasting, and power means for effecting either or both of said adjustments to adapt the machine either for side lasting or for end lasting. Preferably both said adjustments are effected simultaneously and the movement of the wiper is utilized to effect the adjustments either for side or for end lasting or back again to side lasting at the will of the operator. As herein shown, the machine is organized to last the sides of the shoe upper and to secure the upper in place by partially driven tacks of one kind while presenting one edge gage for positioning the shoe in one position and, upon the shift or adjustment being effected, to last the upper at the heel seat and to secure the upper by completely driven tacks of a different kind while presenting another edge gage for different positioning of the shoe, with means, under the control of the operator, for effecting automatically the shifting of this mechanism. It is recognized, of course, as within the invention to provide power means for effecting the shifting of less than all of the mechanisms above referred to.

Another feature of the invention consists in a machine organized for lasting different parts of a shoe upper when shifts are made in the mechanism, such as those referred to,

having means operated by the operator's leg, for example, a knee lever, for effecting any or all of those shifts, thus leaving the operator's hands free to manipulate the shoe and making it possible to control the machine without interrupting its continuity of operation.

Another feature of the invention consists in mechanism constructed and arranged for adjustment to adapt the machine for operating upon different parts of a shoe, and means under the control of the operator to adapt it to effect said adjustment manually when the machine is at rest and to effect the adjustment by power when the machine is running. As shown herein, the adjustment is controlled by means having a given movement when the machine is at rest and a different movement, such as a less movement, when the machine is running. In the illustrated construction, a knee lever is provided which has movement forwardly and rearwardly of the machine and the adjustment is effected by full movement of the knee lever when the machine is at rest. When the machine is running, movement of the knee lever is restricted and the slight movement permitted is effective to cause the adjustment to take place by power.

Another feature of the invention consists in an organization including a gripper, knee operated means for causing plaiting movements to be imparted to the gripper, lasting mechanism for use in conjunction with the plaiting movements, and other lasting means movable into a position for use when the plaiting movements are discontinued, with means for causing power movement of said other lasting means into and out of operative position by movement of the knee operated means in a direction different from the movement which controls the gripper plaiting movements.

These and other features of the invention will appear more fully from the following detailed description when read in connection with the accompanying drawings and will be pointed out in the appended claims.

In the drawings,—

Fig. 1 is a side elevation of a machine embodying the present invention;

Fig. 2 is a plan view of the edge gage mechanism showing the thin edge gage in position for lasting the sides of a shoe;

Fig. 3 is a similar view showing the thick edge gage in position for lasting the heel seat of a shoe;

Fig. 4 is a perspective view of the edge gage mechanism;

Fig. 4^a is a plan view, partly in section, of parts shown in Fig. 4;

Fig. 5 is a detail of mechanism shown in Fig. 4;

Fig. 6 is a plan view, partly in section, of the mechanism for automatically effecting

shifting of the edge gages and tack supplying mechanism;

Fig. 7 is a perspective detail of the mechanism shown in Fig. 6;

Fig. 8 is a detail in plan of parts related to Fig. 6;

Fig. 9 is a side elevation of the lower portion of a machine embodying this invention;

Figs. 10 and 11 are details in plan of parts shown in Fig. 9; and

Fig. 12 is a perspective fragmentary detail of a part shown in Fig. 11.

Referring to Fig. 1 of the drawings, which shows in side view the machine head and the upper portion of the column 2 on which the head is mounted, the numeral 4 indicates a driving pulley on a shaft 6 which carries the cams from which the operative movements of the machine are derived. A gripper 10 is given the usual closing, updraw and overdraw movements by mechanism substantially similar to that shown in the prior patent referred to above. A reciprocating wiper 12 is provided to wipe the tensioned upper into lasted position upon the shoe bottom and a tack is fed in each cycle of the machine from one or the other of two raceways 16, 17 to a pocket in the wiper by which it is carried to position to be driven by a driver 18. The wiper is carried by a horizontally reciprocating slide 13 which is actuated by a lever 14 operated by a cam 15 on the shaft 6. The tacks are partially driven when driver stops 19 are positioned beneath a collar 20 on the driver bar and are completely driven when the stops 19 are removed from beneath the collar 20, the stops being operated by rocking movement of a shaft 21. Mechanism is also provided as in the prior machine for giving the gripper at times lateral and turning movements, these movements being initiated and controlled in extent by movement of a yoke 22 having rolls which engage a groove in a collar 24. Movement of the yoke 22 is effected by rocking movement of a vertical shaft 26 through connections to a knee lever 28, pivoted at 29, lateral movements of which are utilized to rock the shaft 26 by means of mechanism shown in Fig. 9. At its forward end the knee lever carries the usual knee fork 30 which embraces the leg of the operator and is adjustably fixed at 31 to the lever 28. Between its ends the lever 28 carries a roll 34, Fig. 10, which slides in a slot 35 formed in the end of a lever 36 pivoted at 38, Fig. 9, to a bracket 40 on the machine frame and having at the rear of its pivot a toothed segment 42 which engages a correspondingly toothed segment 44 fixed to the rock shaft 26. By the mechanism described lateral movements of the knee lever will rock the shaft 26 to move the yoke 22 and the collar 24 to effect con-

tinued lasting of the shoe.

trol of the lateral and plaiting movements of the gripper. Movement of the lever 36 is limited in either direction by adjustable stops 46, 47 shown in Fig. 9.

5 When the sides of a shoe, for example, a welt shoe, are being lasted, the tacks are driven relatively close to the edge of the sole, preferably in the angle between the feather and the rib or in the portion of the 10 innersole between the channel and the feather known as the "between substance." For this work it is necessary to use an edge gage such as that shown at 48 having a slight vertical extent and known as a thin 15 edge gage. A thin edge gage is necessary in order that the gage may reach into the undercut portions at the shank of the shoe. The tacks used at the sides in welt work must be long lasting tacks and must be only 20 partially driven so that they may be readily removed. Accordingly one of the two raceways 16, 17 is supplied with side lasting tacks and is shifted into position to supply these tacks to the wiper during the side 25 lasting operation. At the same time the driver stops 19 are located under the collar 20 to limit movement of the driver to the required amount. In lasting the sides, it is 30 frequently desirable to employ the lateral and plaiting movements of the gripper and these are introduced and controlled by lateral movements of the fork 30 through the mechanism described.

When the heel seat is being lasted, it is 35 desirable to employ another kind of tack which is suitable for heel seat lasting and to drive the tack completely in and clinch it upon the iron heel plate of the last. Accordingly the other of the two raceways 16, 40 17 is supplied with heel seat lasting tacks, and when these tacks are being used the driver stops 19 are removed from beneath the collar 20. The heel seat tacks should be located at a greater distance from the 45 edge of the sole than are the side lasting tacks and, in order properly to press the upper materials including the counter or heel stiffener against the last, a different form of edge gage is necessary, for example, 50 one having considerable vertical extent and having a contour to force in the upper materials adjacent to the edge of the sole. For this work a gage 50, known as a thick edge gage, is employed.

55 The edge gages and the mechanism for shifting them into position for alternative use and for changing their position relatively to the point at which the tack is driven, is shown in detail in Figs. 2, 3, 4 and 5. The edge gage mechanism is all carried by a block 56 having a slot 58 through which passes a cap screw 60 by which the block 56 is adjustably held in fixed position upon the frame of the machine head, the 60 block being guided for backward and for-

ward adjustment when the screw 60 is loosened by a rib 61 which engages a corresponding groove in the machine frame. The block 56 has a T-guide upon its lower face in which there is mounted a slide 62 having 70 an opening 64 to permit access to the screw 60 for adjusting the block 56 and to permit movement of the slide 62 relatively to the block 56. The forward end of the slide 62 is provided with ears through which passes 75 a pintle 65 upon which the gage 48 and the part 49 which carries the gage 50 are pivoted. The gage 48 is maintained normally in the position shown in Fig. 2 by a spring plunger 80 85 90 95 100 105 110 115 120 125 130 135 140 145 150 155 160 165 170 175 180 185 190 195 200 205 210 215 220 ment of the link 70 the slotted arm 80, since its end is held from movement by the lug 82, causes the bearing 78 of the rock shaft 76 and hence the slide 62 to be moved rearwardly carrying with it, of course, both gages. During this rearward movement of the slide 62 the thick edge rest 50 is swung up into operative position by means of a curved arm 90 fixed to the lower end of the rock shaft 76 by a split clamp 91 and extending around the screw 60 so as to be out of the way of the screw in making adjustments of the block 56. On the end of the arm 90 is a ball 92 which enters a hole in a link 94. The link 94 at its forward end has a sleeve 96 mounted on a pin 98 which is fixed in the part 49 which carries the part 51 and the edge gage 50. Upon clockwise movement of the rock shaft 76, the arm 90 is swung forward pushing upon the link 94 and swinging the gage 50 into operative position, the slide 62 and gages being at the same time retracted as described to locate the gages farther to the rear of the point where the tack is driven and hence positioning the shoe to receive a tack at a greater distance from the edge of the sole. When the parts are in the position shown in Fig. 2, it will be noted that the slot 84 in the block 56 and the slot in the arm 80 extend in the same direction so that adjustment of the slotted arm 80 has no effect upon the position of either gage. The amount of movement which will be imparted to the slide 62, however, when the gage 50 is swung into position depends upon the position of the lug 82 upon the arm 80 in the slot 84.

To set the gages for a kind of work in hand, it is preferable first to position the parts as shown in Fig. 2, and then by loosening the screw 60 to adjust the block 56 to locate the gage 48 so that the side lasting tacks will be driven in the proper location. The screw 60 is then set up and the gage 48 will then always be in the proper position for this kind of work when the thick gage is swung down. The thick edge gage is next swung up to bring the parts in position shown in Fig. 3. The nut 86 is loosened and the slotted arm 80 is slid in or out to locate the thick edge gage 50 to position the shoe for the reception of tacks at the proper distance from the sole edge, which distance will be greater than the distance of the side lasting tacks from the sole edge. By reason of the inclination of the slotted arm 80 to the direction of extent of the slot 84 when the parts are in this position, the slide 62 and hence the gage 50 will be moved forwardly or rearwardly when the arm 80 is adjusted.

In the machine embodying the present invention, the shifting of the thick edge gage into and out of operative position, the shifting of the position of the edge gages rela-

tively to the point at which the tack is driven to locate the tacks at different distances from the sole edge, the shifting of the raceways to cause different kinds of tacks to be delivered to the wiper, and the changing of the driver stroke, are effected automatically when the machine is running by means which is under the control of the operator through the knee lever. When the machine is at rest, the organization is such that the above changes may be made by a greater movement of the knee lever. The mechanism for effecting these results will now be described with particular reference to Figs. 6 and 9. In Fig. 9 is shown the usual counter shaft having a pulley 100 constantly driven by power and a pulley 102 which is belted to the pulley 4 on the shaft 6. The pulley 102 is driven by the pulley 100 through a friction clutch 104 which is set by movement of a wedge 106 effected by depression of a treadle 108. At the same time a member 110 connected to a rod 112 is raised to lift a brake 113 from the pulley 4. An arm 114 has a downward projection 116 pivoted at 118 to the bracket 40. The end of the arm 114 is bifurcated to embrace the rod 112 and rest upon the member 110 Fig. 11. Extending forwardly from the arm 114 is a pin 120 which, when the member 110 is raised by the treadle, enters a notch 122 Fig 12, formed in the lower end of a tubular rock shaft or sleeve 124 which encloses the rock shaft 26. Clamped to the sleeve 124 is a crooked arm 126 which, at its lower end, carries the pivot 29 of the knee lever 28. By reason of the roll and slot connection 34, 35 of the lever 28 with the lever 36, the knee lever 28 may be moved in the direction of its length and such movement is effected by pushing on the fork 30 which will swing the crooked arm 126 and rotate the sleeve 124. A spring 128 is arranged to return the sleeve to initial position when pressure on the fork 30 is released. When the machine is not running, the parts are in the position shown in Fig. 9 where the pin 120 is out of engagement with the notch 122. Hence considerable movement may be given to the sleeve 124. If, however, the treadle is depressed and hence the machine is running, the arm 114 will be raised and the pin 120 will engage the notch 122 in the sleeve 124 and limit the amount of rotation which may be given to the sleeve by pressing against the fork 30. Rotation of the sleeve 124 is utilized to effect or initiate, as the case may be, the shifting of the gages and other mechanism by mechanism best shown in Fig. 6. To the upper end of the sleeve 124 is secured an arm 130 carrying a pawl 132 which is held by a spring 134 in engagement with a six-toothed ratchet 136 mounted to turn freely on the shaft 26. Beneath the ratchet 136 and fixed thereto is a three-projection cam 138. Co-operating with the cam 130

138 are rolls 140, 142 mounted on a member 144 arranged to embrace the shaft 26 and to be moved forwardly and rearwardly by action of the cam 138 upon the rolls 140, 142 5 when the cam is rotated. When the machine is at rest and therefore full movement can be given to the sleeve 124 by the knee lever, the pawl 132 will rotate the ratchet 136 and the cam 138 one-sixth of a revolution and the roll 140 will pass from the position shown in Fig. 6 where it is engagement with one of the high points of the cam 138 to a low portion of the cam, the roll 142 meantime being engaged by a high point of the 10 cam and forced rearwardly carrying with it, of course, the member 144. The member 144 is pivoted at 146 to a block 148 fixed to a vertical shaft 150 with which it turns. Rearwardly of the shaft 150, the block 148 15 is connected by a headed pin 152 to the link 70, the pin being held in the block by a set screw 154. Forwardly of the shaft 150 (see Fig. 7) is a pivot pin 156 on a yoke piece 158 which embraces a projection 160 on the block 148 and which is clamped thereto by a washer 162 and nut 164. Threaded through the bar of the yoke piece 158 is an adjusting screw 166 which engages the projection 160 and is held in adjusted position 20 by a set nut 168. A link comprising two parts 170, 172, Fig. 6, threaded together and held by a set nut 174 has one part 170 pivoted upon the pin 156 and the other part 172 has a ball on its end seated in a recess 25 in the side of the double raceway 16, 17 and held in position by a ball cap 176. Alignment of the raceway 17 with the separating joint 178 of the separating mechanism may be secured by turning the part 172 in the 30 part 170 and tightening the nut 174. When the member 144 is moved as described by rotation of the sleeve 124, the block 148 is rotated with the shaft 150 and operates the link 70 to shift the gages as has been described. Also, through the link comprising the parts 170, 172, the raceway is shifted to bring the column of tacks in one raceway or the other opposite the separating point 178. When the block 148 has been moved to 35 bring the raceway 16 opposite the separating point, the nut 164 may be loosened and the screw 166 adjusted to bring the raceway 16 exactly opposite the separating point 178, the throw of the link effected by the block 148 being thereby varied. The links 170, 172 40 constitute one member of a toggle, the other member of the toggle being represented by the distance from the axis of the shaft 150 to the pin 156, which pin is the central pivot 45 of the toggle. The yoke 158 and screw 166 constitute means for adjusting the length of the toggle member represented by the distance from the shaft 150 to the pivot 156 and the screw 166 provides a fine adjustment for 50 the length of the toggle member. The shaft

150 has at its upper end an arm (not shown) connected by a link 180 (Fig. 1) to an arm 182 which is fixed to the lower end of the rock shaft 21 which at its upper end has the usual connections for operating the driver 70 stops 19 so that the stroke of the driver will be shifted coincidently with the shifting of the edge gages.

When the machine is running, the pin 120 engages the notch 122 in the sleeve 124 and 75 limits its rotation. Sufficient movement is, however, still provided to move the toothed ratchet from the position as shown in Fig. 6 where it will not be operated by a pawl 190 to a position where it will be engaged by the pawl 132. The pawl 190 is pivoted at 192 to a part 194 carried by the wiper slide 13 which has a power effected forward and backward movement during the operation of the machine. After movement of the ratchet 136 80 has been initiated by movement of the pawl 132 through rearward pressure of the fork 30 which, of course, is under the control of the operator, the pawl 190 picks up a tooth on the ratchet 136 and continues its movement to complete one-sixth of its revolution and effect shifting of the parts by direct application of the power of the machine as described. Movement of the pawl 132 when it returns to its rearward position, is insufficient to cause it to pick up the next tooth of the ratchet until movement of the ratchet is initiated by the operator whereupon the machine will automatically shift the parts 85 back to their original position. The pawl 190 is held in engagement with the ratchet 136 by a spring 196 connected between pins 198, 200 located respectively on the pawl and on a part secured to the slide 13. To prevent accidental or unintended movement 90 of the ratchet 136 mechanism shown in Fig. 8 is provided. The ratchet 136 has a hub 202 which is embraced by a strap 204 on a member 206 which has mounted therein a spring plunger 208 arranged to engage one 95 of six suitable recesses 209 in the hub 202. The member 206 is provided with a lug 208 through which passes a rod 210 arranged to engage an angle of the machine frame and hold the member 206 against rotation when 100 fastened by a set screw 207.

The edge gage member 50 has been described as carried by two parts 49, 51 as 105 shown in Fig. 4. These parts are connected together by a bolt 212 on which is a spring 214 arranged to press the members 49, 51 together. In one of the parts for example 51 is a recess and in the other part 49 is a pin 53 adapted to enter the recess when the parts are in the position shown in Figs. 4 and 4^a 110 and which may be forced out of the recess against the tension of the spring 214 to allow the parts 49, 51 to turn relatively on the bolt 212. This allows the gage member 50 and part 51 to be folded back beyond its 115

normal inoperative position if more room is desired when the thin edge gage is in use. This yielding joint also prevents accident in case the operator has his fingers in the path of the thick edge gage at the time when it is automatically thrown into operative position by power.

Having thus described the invention, what is claimed as new and desired to be secured by Letters Patent of the United States is:—

1. In a machine of the class described, the combination of a gripper for working successive portions of an upper over a last, fastening inserting means for securing the upper in position, and knee-controlled means for enabling the attendant to alter at will the operation of the fastening inserting mechanism while maintaining unchanged the operation of the gripper.
  2. In a machine of the class described, the combination of a gripper and actuating means therefor to work successive portions of an upper over a last, means for imparting plaiting movements to the gripper, a knee lever movable in one direction for controlling at will said plaiting movements, fastening inserting mechanism, and means for modifying the action of said fastening inserting mechanism which means is controlled at will by movement of said knee lever in another direction.
  3. A machine of the class described having, in combination, lasting mechanism for performing, when in one condition of adjustment, the operation of lasting a side of a shoe, said means being constructed and arranged to be shifted during a single cycle of the machine into another condition of adjustment for performing the operation of lasting an end of the shoe, and power means under control of the operator for effecting the shifting of the mechanism from condition of adjustment for performing side lasting into condition of adjustment for performing and lasting.
  4. A machine of the class described having, in combination, lasting and securing mechanism for performing, when in one condition, the operation of lasting and securing the upper of a shoe at the side, said mechanism being constructed and arranged to be shifted into another condition for performing the operation of lasting and securing the upper at an end of the shoe, and means, under control of the operator, for effecting the shifting of the mechanism in time relation to the operation of the machine from condition for the side lasting operation into condition for the end lasting operation.
  5. In a machine of the class described, the combination of tacking means, edge gage mechanism, means for relatively positioning the tacking means and the edge gage mechanism to cause tacks to be driven into the shoe at one distance from the sole edge
- constructed and arranged to shift relatively the tacking means and the edge gage mechanism to cause the tacks to be driven at another distance from the sole edge, and power means for effecting said relative shifting to change the location of the tack relatively to the shoe edge.
6. In a machine of the class described, the combination of tacking means, edge gage mechanism, means for relatively positioning the tacking means and the edge gage mechanism to cause tacks to be driven into the shoe at one distance from the sole edge constructed and arranged to shift relatively the tacking means and the edge gage mechanism to cause the tacks to be driven at another distance from the sole edge, power means for effecting said relative shifting to change the location of the tack relatively to the shoe edge, and manual means for initiating the action of the power means.
  7. In a machine of the class described, the combination of two edge gages either of which may be used to the exclusion of the other, means for relatively shifting the gages to render either gage operative, and power means for operating the shifting means.
  8. In a machine of the class described, the combination of tacking means, lasting means, one gage to position the shoe for the reception of tacks at one distance from the sole edge, another gage to position the shoe for the reception of tacks at another distance from the sole edge, said gages being constructed and arranged for relative shifting to enable each to be used to the exclusion of the other, and power means under control of the operator for shifting the gages to change the location of the tacks relatively to the sole edge.
  9. In a machine of the class described, the combination of tacking means, lasting means, one gage to position the shoe for the reception of tacks at one distance from the sole edge, another gage to locate the shoe for the reception of tacks at another distance from the shoe edge, and power means under control of the operator for relatively shifting the gages to change the location of the tacks relatively to the last edge.
  10. In a machine of the class described, the combination of tacking means, lasting means, a thin edge gage to position the shoe for the reception of tacks at a short distance from the sole edge, a thick edge gage arranged to be moved into operative position to locate the shoe for the reception of tacks at a greater distance from the shoe edge, and power means for shifting the thick gage to change the location of the tracks relatively to the last edge.
  11. In a machine of the class described,

the combination of tacking means, lasting means, a thin edge gage to position the shoe for the reception of tacks at a short distance from the sole edge, a thick edge gage arranged to be moved into operative position to locate the shoe for the reception of tacks at a greater distance from the shoe edge, power means for shifting the thick gage to change the location of the tacks relatively to the last edge, and manual means for initiating the action of the power means.

12. In a machine of the class described, the combination of two edge gages constructed and arranged to be used each to the exclusion of the other and against either of which a shoe is held by both hands of the workman, tack driving means constructed and arranged to effect either partial or complete insertion of tacks, and knee controlled power operated means for relatively shifting the gages to render one of the gages operative and the other inoperative and for changing the operation of the tack driving means.

13. In a machine of the class described, the combination of tacking means, edge gage mechanism, means for relatively positioning the tacking means and the edge gage mechanism to cause tacks to be driven into the shoe at one distance from the sole edge constructed and arranged to shift relatively the tacking means and the edge gage mechanism to cause the tacks to be driven at another distance from the sole edge, and means operable by the operator when the machine is stopped to effect said relative shifting and operable when the machine is running to cause said relative shifting to take place by power.

14. In a machine of the class described, the combination of tacking means, edge gage mechanism, means for relatively positioning the tacking means and the edge gage mechanism to cause tacks to be driven into the shoe at one distance from the sole edge constructed and arranged to shift relatively the tacking means and the edge gage mechanism to cause the tacks to be driven at another distance from the sole edge, and means movable to one extent when the machine is at rest to effect said relative shifting and movable to another extent when the machine is running to cause said relative shifting to take place by power.

15. In a machine of the class described, the combination of tacking means, edge gage mechanism, means for relatively positioning the tacking means and the edge gage mechanism to cause tacks to be driven into the shoe at one distance from the sole edge constructed and arranged to shift relatively the tacking means and the edge gage mechanism to cause the tacks to be driven at another distance from the sole edge, and means movable when the machine is at rest to effect said relative shifting and movable to a lim-

ited extent when the machine is running to cause the relative shifting to take place by power.

16. In a machine of the class described, the combination of tacking means, edge gage mechanism, means for relatively positioning the tacking means and the edge gage mechanism to cause tacks to be driven into the shoe at one distance from the sole edge constructed and arranged to shift relatively the tacking means and the edge gage mechanism to cause the tacks to be driven at another distance from the sole edge, and means under manual control to initiate the shifting and cause the shifting to be completed by power.

17. In a machine of the class described, the combination of two edge gages constructed and arranged for alternative use, means constructed and arranged to effect relative movement of said gages by power when the machine is running to render either gage operative, and means constructed and arranged for operation when the machine is at rest to effect said relative movement manually.

18. In a machine of the class described, the combination of tacking means, lasting means, one edge gage to position the shoe for the reception of tacks at one distance from the sole edge, another edge gage to locate the shoe for the reception of tacks at another distance from the shoe edge, said gages being constructed and arranged to be relatively shifted to enable each to be used to the exclusion of the other, and means movable by the operator when the machine is stopped to effect shifting of the gages and movable when the machine is running to cause the gages to be shifted by power.

19. In a machine of the class described, the combination of tacking means, lasting means, one edge gage to position the shoe for the reception of tacks at one distance from the sole edge, another edge gage to locate the shoe for the reception of tacks at another distance from the shoe edge, said gages being constructed and arranged to be relatively shifted to enable each to be used to the exclusion of the other, and means movable to one extent when the machine is at rest to effect shifting of the gages and movable to another extent when the machine is running to cause the gages to be shifted by power.

20. In a machine of the class described, the combination of tacking means, lasting means, one edge gage to position the shoe for the reception of tacks at one distance from the sole edge, another edge gage to locate the shoe for the reception of tacks at another distance from the shoe edge, said gages being constructed and arranged to be shifted to enable each to be used to the exclusion of the other, and means movable when the machine is at rest to effect shift-

ing of the gages and movable to a less extent when the machine is running to cause the shifting to be effected without attention on the part of the operator.

- 5 21. In a machine of the class described, the combination of tacking means, lasting means, one edge gage to position the shoe for the reception of tacks at one distance from the sole edge, another edge gage to 70 locate the shoe for the reception of tacks at another distance from the shoe edge, said gages being constructed and arranged to be shifted to enable each to be used to the exclusion of the other, and means movable 75 manually when the machine is at rest to effect shifting of the gages and movable when the machine is running to initiate the shifting of the gages and cause the shift to be completed by movement of the machine.
22. In a machine of the class described, 80 tack driving means constructed and arranged for adjustment to insert tacks either partially or completely, power means for effecting said adjustment of the driving means, and means for manually controlling said power means.

23. In a lasting machine, the combination of tack driving means constructed and arranged for adjustment to insert tacks either 85 partially or completely, lasting means constructed and arranged for adjustment to modify its lasting effect according as the tacks are partially or completely inserted, a knee lever, and connections to cause either 90 or both said adjustments to be effected by movement of the knee lever.

24. In a lasting machine, the combination of tack driving means constructed and arranged for adjustment to effect either complete or partial insertion of tacks, a gripper, means for imparting plaiting movements to the gripper, a knee lever, a connection from the knee lever to control the 95 plaiting movements of the gripper, and a connection to the knee lever to cause adjustment of the tack driving means, said connections being operable by the knee lever each to the exclusion of the other while the machine is in operation and while the shoe is upheld to the machine in both hands of the operator.

25. In a machine of the class described, the combination of lasting means including a wiper which is moved repeatedly over the shoe bottom, mechanism for partially inserting tacks of one kind constructed and arranged to be shifted fully to insert tacks of another kind, and power means to effect shifting of said mechanism at the will of 110 the operator.

26. In a machine of the class described, the combination of tack driving means constructed and arranged for adjustment to effect either partial or complete insertion of tacks, means adapted to be operated when

the machine is running to cause said adjustment to be effected by power, and means constructed and arranged for manual operation when the machine is at rest to effect said adjustment.

27. In a machine of the class described, the combination of tack driving means, means constructed and arranged for adjustment to cause the tack to be either partially or completely driven by the driver, and means constructed and arranged by a slight movement thereof when the machine is running to cause the adjustment of the tack driving means, said means being movable to a greater extent when the machine is at rest to effect adjustment of the tack driving means manually.

28. In a machine of the class described, tack driving means, means constructed and arranged for adjustment to supply either 85 of a plurality of kinds of tacks to the driver, power means for effecting said adjustment, and means for manually controlling said power means.

29. In a machine of the class described, 90 the combination of tack driving means to which the shoe is upheld only by the operator's hands, means organized for adjustment to supply either of a plurality of kinds of tacks to the driver, a gripper, gripper 95 operating mechanism organized to impart plaiting movements to the gripper and for adjustment to modify the plaiting movements, and means arranged for combined or selective movements by a limb of the operator to control the kind of tack supplied 100 and to impart or discontinue the plaiting movements of the gripper.

30. In a lasting machine, the combination of a gripper for working successive portions of an upper over a last upheld by both hands of the operator, a wiper for laying successive portions of the overworked upper against the last bottom, means for supplying either of a plurality of kinds of tacks to the wiper, 105 tack driving means, a knee lever arranged for movement in different directions, and connections from the knee lever to the gripper and to the tack supplying means to cause the action of the gripper to be modified when the knee lever is moved in one direction 110 and to cause a change in the kind of tack supplied when the knee lever is moved in another direction.

31. In a machine of the class described, 120 the combination of tack driving means, means constructed and arranged for adjustment to supply either of a plurality of kinds of tacks to the driver, means constructed and arranged to cause said adjustment to 125 be made by power when the machine is running, and means constructed and arranged to be operated when the machine is at rest to effect said adjustment manually.

32. In a machine of the class described, 130

- the combination of tack driving means, means constructed and arranged for adjustment to supply either of a plurality of kinds of tacks to the driver, and means constructed and arranged by a slight movement thereof when the machine is running to cause the adjustment of the tack supplying means for supplying another kind of tack, said means being movable to a greater extent 5 when the machine is at rest to effect adjustment of the tack supplying means manually.
33. In a machine of the class described, a double raceway, a separator to take tacks from either raceway, toggle means for moving the raceway, and means for varying the length of one member of the toggle comprising a sliding yoke carrying the central pivot of the toggle and a screw for adjusting 10 the position of the yoke.
34. In a machine of the class described, the combination of a double raceway, a separator adapted to take tacks from either raceway, toggle means for moving the raceway, and means for varying the throw of the toggle comprising a member carrying the central pivot of the toggle, a fine adjustment for the member, and means for holding the member rigidly in adjusted position.
35. A machine of the class described having, in combination, lasting mechanism for lasting one portion of a shoe, said mechanism being constructed and arranged to be shifted to adapt it for lasting another portion of 15 the shoe, and means under control of the operator for effecting by power the shifting of the mechanism for performing its operation upon either part of the shoe.
36. In a machine of the class described, the combination of means for progressively lasting and securing an upper at the one part of a shoe, shoe positioning means constructed and arranged for adjustment to adapt said lasting and securing means for treating the 20 upper at another part of the shoe, and means under the control of the operator for causing adjustment of said positioning means to be effected in time relation to movement of the machine when passing from one part of the 25 shoe to the other part of the shoe.
37. In a machine of the class described, the combination of means for progressively lasting and securing an upper at the side of a shoe, shoe positioning means constructed and arranged for adjustment to adapt said lasting and securing means for treating the upper at an end of the shoe, and means under the control of the operator for causing adjustment of said positioning means to be 30 effected by movement of the machine and in a single cycle when passing from the side of the shoe to the end of the shoe.
38. A machine of the class described having, in combination, lasting mechanism for 35 lasting and tacking one portion of a shoe, said mechanism being constructed and arranged to be shifted to adapt it for lasting and tacking another portion of the shoe, and power means under control of the operator for effecting the shifting of the mechanism for performing its operation upon either part of the shoe.
39. A machine of the class described having, in combination, lasting means including a wiper constructed and arranged for repeated operation to last progressively an upper over a shoe bottom, means for securing the upper, mechanism constructed and arranged upon one adjustment to adapt the machine for operating upon the side of the 40 shoe and upon another adjustment to adapt the machine for operating upon the end of the shoe, and power means under control of the operator for effecting the adjustments of said mechanism.
40. In a machine of the class described, the combination of lasting means including a wiper for progressively lasting either the side or an end of a shoe, securing mechanism adapted to secure the upper at the side of the shoe constructed and arranged for adjustment to adapt it for securing the upper at the end of the shoe, and means under the operator's control to cause said adjustments to be effected by power in passing 45 from side lasting to end lasting or vice versa.
41. A machine of the class described having, in combination, lasting means including a wiper moved repeatedly over a shoe bottom for progressively lasting the sides and end of a shoe, securing mechanism adapted to secure the upper at the side of the shoe constructed and arranged for a change of adjustment to adapt it for securing the upper at the end of the shoe, and means operated by the wiper at the will of the operator to effect said adjustment in passing from side lasting to end lasting or from end lasting to side lasting.
42. A machine of the class described having, in combination, lasting means including a wiper moved repeatedly over a shoe bottom for progressively lasting the sides and end of a shoe, securing mechanism adapted to secure the upper at the side of the shoe constructed and arranged for a 50 change of adjustment to adapt it for securing the upper at the end of the shoe, a knee lever, and means for effecting said change of adjustment by movement which is initiated by the knee lever and completed by the wiper.
43. A machine of the class described having, in combination, lasting means including a wiper moved repeatedly over a shoe bottom for progressively lasting the sides and end of a shoe, securing mechanism adapted to secure the upper at the side of the shoe constructed and arranged for a change of adjustment to adapt it for securing 55

ing the upper at the end of the shoe, a knee lever, and means controlled by the knee lever for causing said change of adjustment to be effected by power.

- 5 44. A machine of the class described having, in combination, lasting means including a wiper moved repeatedly over a shoe bottom for progressively lasting the sides and end of a shoe, securing mechanism adapted to secure the upper at the side of the shoe constructed and arranged to adapt it for securing the upper at the end of the shoe, positioning means adapted to position the shoe for side lasting constructed and arranged for adjustment to adapt it to position the shoe for end lasting, a knee lever, and means for effecting said adjustment by movement which is initiated by the knee lever and completed by the wiper.
- 10 45. A machine of the class described having, in combination, lasting means including a wiper moved repeatedly over a shoe bottom for progressively lasting the sides and end of a shoe, securing mechanism adapted to secure the upper at the side of the shoe constructed and arranged for a change of adjustment to adapt it for securing the upper at the end of the shoe, a knee lever, and means under control of the knee lever to cause the wiper upon one movement to effect said adjustment and upon another movement in the same direction to restore the parts to initial positions.

- 20 46. A machine of the class described having, in combination, lasting means including a wiper moved repeatedly over a shoe bottom for progressively lasting the sides and end of a shoe, securing mechanism adapted to secure the upper at the side of the shoe constructed and arranged for a change of adjustment to adapt it for securing the upper at the end of the shoe, a knee lever, and means controlled by one movement of the knee lever to cause said adjustments to be effected by power and by another similar movement to cause restoration of the parts to the original adjustment by power.

- 25 47. In a machine of the class described, the combination of lasting means including a wiper for progressively lasting the side or end of a shoe, securing mechanism adapted to secure the upper at the side of the shoe constructed and arranged for adjustment to adapt it for securing the upper at the end of the shoe, positioning means adapted to position the shoe for side lasting constructed and arranged for adjustment to adapt it to position the shoe for end lasting, and means under the operator's control to cause said adjustments to be effected by power in passing from side lasting to end lasting or vice versa.

- 30 48. A machine of the class described having, in combination, lasting means including a wiper moved repeatedly over a shoe bottom for progressively lasting the sides and end of a shoe, securing mechanism adapted to secure the upper at the side of the shoe constructed and arranged to adapt it for securing the upper at the end of the shoe, positioning means adapted to position the shoe for side lasting constructed and arranged for adjustment to adapt it to position the shoe for end lasting, and means operated by the wiper at the will of the operator to effect said adjustments in passing from side lasting to end lasting or from end lasting to side lasting.

- 35 49. A machine of the class described having, in combination, lasting means including a wiper moved repeatedly over a shoe bottom for progressively lasting the sides and end of a shoe, securing mechanism adapted to secure the upper at the side of the shoe constructed and arranged to adapt it for securing the upper at the end of the shoe, positioning means adapted to position the shoe for side lasting constructed and arranged for adjustment to adapt it to position the shoe for end lasting, a knee lever, and means controlled by the knee lever for causing said adjustments to be effected by power.

40 50. A machine of the class described having, in combination, lasting means including a wiper moved repeatedly over a shoe bottom for progressively lasting the sides and end of a shoe, securing mechanism adapted to secure the upper at the side of the shoe constructed and arranged to adapt it for securing the upper at the end of the shoe, positioning means adapted to position the shoe for side lasting constructed and arranged for adjustment to adapt it to position the shoe for end lasting, a knee lever, and means controlled by the knee lever and completed by the wiper.

45 51. A machine of the class described having, in combination, lasting means including a wiper moved repeatedly over a shoe bottom for progressively lasting the sides and end of a shoe, securing mechanism adapted to secure the upper at the side of the shoe constructed and arranged to adapt it for securing the upper at the end of the shoe, positioning means adapted to position the shoe for side lasting constructed and arranged for adjustment to adapt it to position the shoe for end lasting, a knee lever, and means controlled by the knee lever for causing said adjustments to be effected by power.

50 52. A machine of the class described having, in combination, lasting means including a wiper moved repeatedly over a shoe bottom for progressively lasting the sides and end of a shoe, securing mechanism adapted to secure the upper at the side of the shoe constructed and arranged to adapt it for securing the upper at the end of the shoe, positioning means adapted to position the shoe for side lasting constructed and arranged for adjustment to adapt it to position the shoe for end lasting, a knee lever, and means under control of the knee lever to cause the wiper upon one movement to effect said adjustment and upon another movement in the same direction to restore the parts to initial positions.

55 53. A machine of the class described having, in combination, lasting means including a wiper moved repeatedly over a shoe bottom for progressively lasting the sides and end of a shoe, securing mechanism adapted to secure the upper at the side of the shoe constructed and arranged for adjustment to adapt it for securing the upper at the end of the shoe, positioning means adapted to position the shoe for side lasting constructed and arranged for adjustment to adapt it to position the shoe for end lasting, a knee lever, and means controlled by one movement of the knee lever to cause said adjustments to be effected by power and another similar movement to cause restoration of the parts to the original adjustment.

58 54. In a machine of the class described, the combination of lasting means including

a wiper which is moved repeatedly over the shoe bottom, mechanism for partially inserting tacks of one kind constructed and arranged to be shifted fully to insert tacks of another kind, a plurality of edge gages, mechanism arranged to be shifted to present either of the gages in position for use to the exclusion of the other gage, and power means to effect shifting of both said mechanisms at the will of the operator.

53. In a machine of the class described, the combination of lasting means including a wiper which is moved repeatedly over the shoe bottom, mechanism for partially inserting tacks of one kind constructed and arranged to be shifted fully to insert tacks of another kind, a plurality of edge gages, mechanism arranged to be shifted to present either of the gages in position for use to the exclusion of the other gage, and means under the control of the operator to cause movements of the wiper to effect shifting of both said mechanisms.

54. A machine of the class described having, in combination, mechanism organized for adjustment to effect either of two operations upon a shoe, means for effecting said adjustment which is operable at times to effect said adjustment manually and at times to cause said adjustment to be effected by power, and means for controlling the operation of the machine, said means being constructed and arranged to determine from its position whether the means for effecting the adjustment will be operated manually or by power.

55. In a lasting machine, the combination of means including a gripper for working successive portions of an upper over a last, means for causing the gripper to plait the upper, a knee lever movable in one direction to control the plaiting movement of the gripper, a thin edge rest for use in lasting one portion of the shoe, a thick edge rest for lasting another portion of the shoe, and means operated by a different movement of the knee lever for moving the thick edge rest into and out of operative position.

56. In a machine of the class described, the combination of lasting mechanism, and an edge gage for positioning the shoe relatively to the lasting mechanism constructed and arranged for movement into and out of operative position and having a yielding pivot to permit the shoe engaging portion of the gage to have increased movement out of operative position.

57. In a machine of the class described, the combination of lasting mechanism, an edge gage for positioning the shoe relatively to the lasting mechanism constructed and arranged for movement into and out of operative position, power means for moving the gage, and means for permitting a portion

of the gage to yield in case its movement by power is obstructed.

58. In a machine of the class described, the combination of an edge gage mounted for movement into and out of operative position, power means under control of the operator for moving the gage into operative position, and means permitting the shoe engaging portion of the gage to yield if it meets an obstruction without affecting the power movement of the other portion of the gage.

59. In a machine of the class described, the combination of an edge gage, relatively movable members upon which the gage is mounted, means for swinging the members carrying the gage into and out of operative position, and frictional means between said relatively movable members to hold them normally in predetermined relation.

60. In a lasting machine, the combination of a tack driver, tack supplying mechanism constructed and arranged to be differently positioned to supply tacks of different kinds to the driver, driver controlling means constructed and arranged for movement to cause the driver to drive tacks in the work to different extents, means for shifting the position of the tack supplying means and the driver control to cause at one time one kind of tack to be delivered and driven to one extent and at another time to cause another kind of tack to be delivered and driven to another extent, and power means for shifting the tack supplying means and the driver controlling means.

61. In a machine of the class described, fastening inserting mechanism, a gage constructed and arranged to position the work relatively to the fastening inserting mechanism, power operated means for controlling the movement of the gage both toward and from the plane of operation of the fastening inserting mechanism, and normally stationary means movable by the operator at any time in the cycle of operations of the machine to render the power operated means operable to cause movement of the gage.

62. In a lasting machine, the combination of two edge gages constructed and arranged to be shifted into and out of operative position each to the exclusion of the other and against either of which, when in operative position, a shoe is held by both hands of the operator, lasting means constructed and arranged for adjustment in accordance with the edge gage in use, and knee operated means constructed and arranged for movement to cause at will adjustment of the lasting means and shifting of the edge gages.

63. In a lasting machine, the combination of two edge gages constructed and arranged to be shifted into and out of operative posi-

- tion each to the exclusion of the other, and against either of which a shoe is held in both hands of the operator, lasting means constructed and arranged for adjustment to modify its action, and knee operated means by movement of which the edge gages may be caused to be shifted and the lasting means adjusted either independently or together.
64. In a lasting machine, the combination 10 of a gripper, mechanism adapted to be rendered operative or inoperative to impart plaiting movements to the gripper, shoe positioning means adapted for adjustment differently to position the work, and means to 15 which force is applied by a limb of the operator to control operation of the plaiting mechanism and adjustment of the positioning means either separately or together.
65. In a lasting machine, the combination 20 of a gripper, mechanism adapted to be rendered operative or inoperative to impart plaiting movements to the gripper, shoe positioning means adapted for adjustment differently to position the work, and a single 25 means movable in different directions by a limb of the operator and arranged when moved in one direction to control the plaiting mechanism and when moved in another direction to cause adjustment of the shoe 30 positioning means.
66. In a lasting machine, the combination of a rest against which a shoe is held by both hands of the operator, tack driving means constructed and arranged to effect by 35 adjustment either partial or complete insertion of tacks, means for supplying either of a plurality of kinds of tacks, and knee controlled power operated means for causing simultaneously adjustment of the driving 40 means and a change in the kind of tack supplied.
67. In a lasting machine, the combination 45 of tack driving means constructed and arranged for adjustment to insert tacks either partially or completely, lasting means constructed and arranged for adjustment to modify its lasting effect according as the tacks are partially or completely inserted, a knee lever, a shaft, a sleeve on the shaft, 50 connections from the shaft to the lasting means and from the sleeve to the tack driving means, and connections from the knee lever to both the shaft and sleeve to cause movement of either or both to be effected by 55 movement of the knee lever.
68. In a lasting machine, the combination 60 of tack driving means constructed and arranged for adjustment to effect either complete or partial insertion of tacks, a gripper, means for imparting plaiting movements to the gripper, a knee lever, a shaft connected to the knee lever to control the plaiting movements of the gripper, and a sleeve connected to the knee lever to cause adjustment 65 of the tack driving means.
69. In a machine of the class described, the combination of tack driving means to which a shoe is presented, means organized for adjustment to supply either of a plurality of kinds of tacks to the driver, a 70 gripper, gripper operating mechanism organized to impart to the gripper plaiting movements and for adjustment to modify the plaiting movements, telescoping rotary members connected one to effect by its rotation adjustment of the gripper operating mechanism and the other to cause by its rotation a change in the kind of tack, and means arranged for movements by a limb of the operator to effect rotation of said members together or separately. 75
70. In a lasting machine, the combination of a gripper for working successive portions of an upper over a last, a wiper for laying successive portions of the overworked upper against the last bottom, means for supplying either of a plurality of kinds of tacks to the wiper, tack driving means, a knee lever arranged for movement in different directions, telescoping shafts, connections 80 from the knee lever to the shafts to effect movement of one shaft when the knee lever is moved in one direction and to effect movement of the other shaft when the knee lever is moved in the other direction, and connections 85 from one shaft to control the action of the gripper and from the other shaft to cause a change in the kind of tack supplied to be effected. 90
71. In a lasting machine, the combination 95 of two edge gages constructed and arranged to be shifted into and out of operative position each to the exclusion of the other and against either of which when in operative position a shoe is held by both hands of the operator, means constructed and arranged for adjustment to supply either of a plurality of kinds of tacks in accordance with the edge gage in use, and knee operated means constructed and arranged upon movement 100 to cause at will application of power to effect adjustment of the tack supplying means and shifting of the edge gages. 105
72. In a lasting machine, the combination 110 of tack supplying means constructed and arranged to be shifted to cause tacks of one kind or tacks of another kind to be supplied, tack driving means, a rest against which a shoe is held in both hands of the operator, lasting means constructed and arranged for 115 adjustment to modify its action, and knee operated means by movement of which the tack supplying means may be caused to be shifted and the lasting means adjusted. 120
73. In a lasting machine, the combination 125 of an edge gage constructed and arranged to be shifted, lasting means constructed and arranged for adjustment to modify its action, a tube element and a shaft element both leading from a point adjacent to the lasting 130

means and the edge gage to a point adjacent to the operator's knee, connections from one of said elements to the lasting means to adjust the same when said element is moved, 5 connections from the other element to the edge gage to cause by its movement shifting of the gage, and knee operated means for moving either the tube element or the shaft element.

74. In a lasting machine, the combination 10 of a gripper mechanism adapted to be rendered operative or inoperative to impart plaiting movements to the gripper, shoe positioning means adapted for adjustment differently to position the work, a shaft connected to the plaiting mechanism arranged for movement to render said mechanism operative or inoperative, a sleeve on said shaft, connections therefrom to cause upon movement of the sleeve adjustment of the work 15 positioning means, and means to which force is applied by a limb of the operator to move either the shaft or the sleeve.

75. In a lasting machine, the combination 20 of a gripper mechanism adapted to be rendered operative or inoperative to impart plaiting movements to the gripper, shoe positioning means adapted for adjustment differently to position the work, a shaft connected to said plaiting mechanism arranged for movement to render said mechanism operative or inoperative, a sleeve on said shaft, connections therefrom to cause adjustment 25 of the work positioning means upon movement of the sleeve and a single means movable in either of two directions by a limb of the operator and arranged when moved in one direction to move the sleeve and when moved in the other direction to move the 30 shaft.

76. In a machine of the class described, 35 the combination of a gripper, means for turning the gripper and moving it laterally to plait the upper, means for supplying tacks

of different kinds, two edge gages for positioning the work, and means operated by the knee of the workman for controlling the gripper plaiting movements causing shifting of the gages and a change in the kind of tacks supplied. 45

77. In a machine of the class described, the combination of a gripper, means for turning the gripper and moving it laterally to plait the upper, means for supplying tacks of two different kinds, means constructed and arranged to cause one kind of tack to be driven partially and another kind completely, and knee-operated means for controlling the plaiting movements of the gripper and determining whether one kind of tack will be completely driven or the other kind partially driven. 50

78. In a machine for lasting successive portions of a shoe upper progressively about the periphery of the shoe, the combination 55 of two edge gages constructed and arranged to be used each to the exclusion of the other and against either of which the shoe is supported in both hands of the operator, and knee-controlled, power operated means for 60 relatively shifting the gages to render either gage operative.

79. In a machine of the class described, the combination of a gripper, means for turning the gripper and moving it laterally to plait 75 the upper, a pair of edge gages relatively movable to present either gage in operative position, means for causing either complete or partial insertion of tacks, a single manually operated means, and connections therefrom to the upper plaiting means, to the gages and to the tack inserting means for 80 controlling the operation of the plaiting means, the relative position of the gages and the degree of insertion of the tacks. 85

In testimony whereof I have signed my name to this specification.

THOMAS H. SEELY.
